Primary Examiner — T Chase Nelson(74) Attorney, Agent, or Firm — Banner & Witcoff, Ltd.CLAIM

The ornamental design for a shoe, as shown and described.

DESCRIPTION

FIG. 1 is a bottom front perspective view of a shoe showing my new design;

FIG. 2 is a bottom view thereof; and,

FIG. 3 is a bottom rear perspective view thereof.

The broken line showing of the elongated curved elements represent grooves that form no part of the claimed design. The broken line showing of the circle and the unshaded region therein represent a region that forms no part of the claimed design. The broken lines depicting the remainder of the shoe form no part of the claimed design.
